UNITED STATES PATENT OFFICE.

JOHN HANCOCK, OF LOUISVILLE, KENTUCKY.

PEG-FLOAT.

SPECIFICATION forming part of Letters Patent No. 224,424, dated February 10, 1880.

Application filed December 18, 1879.

To all whom it may concern:

Be it known that I, JOHN HANCOCK, of Louisville, in the county of Jefferson, and in the State of Kentucky, have invented certain 5 new and useful Improvements in Peg-Floats; and I do hereby declare that the following is a full, clear, and exact description thereof, reference being had to the accompanying drawings, and to the letters of reference marked 10 to thereon, making a part of this specification.

The nature of my invention consists in the construction and arrangement of a peg-float for cutting off the pegs in boots and shoes, as will be hereinafter more fully set forth.

15 In order to enable others skilled in the art to which my invention appertains to make and use the same, I will now proceed to describe its construction and operation, referring to the annexed drawings, in which—

20 Figure 1 is a perspective view of my peg-float. Fig. 2 is an enlarged vertical section of the upper part thereof. Fig. 3 is a front view of the head. Fig. 4 shows one of the knives.

A represents the post or standard, provided 25 with a foot, B, to be fastened to the counter or table.

At the upper end of the post A is formed a curved projecting tenon or arm, C, on the convex side of which, near the upper end, is 30 a groove, at x, as shown in Fig. 2.

D represents the head of the peg-float, made in the convex form shown, and formed with a socket or eye, E, to slip over the curved arm C. This socket or loop is made nearer one 35 end than the other of the head, and when slipped over the arm C a key, a, is passed over the same through the groove x, so as to hold the head in place.

On the under side of the head, at each end, 40 is a recess, d, in which is placed the knife F. The knife is slotted, as shown in Fig. 4, and

fastened by a screw, b. The edge of the knife F projects through a slot, e, in the head, and beyond said slot, in the end of the head, is made a series of grooves, i i, as shown.

45 For cutting off the pegs in the foot and toe and part of the shank the longer end of the head is used. The head is then reversed for cutting the pegs in the heel and adjacent part of the shank.

50 The knives or bits F are ground off on each side at the point, which makes them capable of cutting an iron tack, as well as the pegs. Besides, if there is a ridge of leather made by driving in the pegs this float planes it off and makes a smooth surface for the foot. When the bits become dull they can be easily removed and ground or filed.

55 Having thus fully described my invention, what I claim as new, and desire to secure by Letters Patent, is—

1. In a peg-float, the head or stock D, provided with recesses d, slots e, and grooves i, in combination with the knives or bits F, all constructed substantially as and for the purposes herein set forth.

2. The combination of the standard A, provided with the curved arm C, the reversible head or stock D, provided with the socket or loop E, and the bits F, the socket being to 70 one side of the center, so as to make one end of the head longer than the other, all constructed substantially as and for the purposes herein set forth.

75 In testimony that I claim the foregoing I have hereunto set my hand this 10th day of December, 1879.

JOHN HANCOCK.
